UNITED STATES PATENT OFFICE

NORMAN A. CHASTENAY, OF OZONE PARK, NEW YORK

FOOT APPLIANCE FOR SWIMMERS

Application filed July 19, 1929. Serial No. 379,480.

This invention relates to an improved aquatic appliance adapted for attachment to the hands and feet of long distance swimmers, but susceptible of such practical use by all 5 persons while bathing or swimming.

The invention has been especially designed to afford mechanical propulsion means such as may be attached to both the wrists and ankles of the user to expedite and facilitate 10 movement through the water.

Briefly stated, the invention has reference to an accessory of this class which is characterized principally by a pair of hingedly connected wings of a peculiar configuration, 15 these being embodied in a structure of appropriate weight and design, and such structure being equipped with maintenance straps or other equivalents and whereby to permit attachment to either the ankles or the wrists 20 or both, as desired.

In carrying the invention into practice, I have found it expedient to provide a structure which is distinguishable from analogous prior art devices in that it includes a simplified and economical arrangement of details 25 cooperating in an intimate and practical manner for producing readily usable propulsion means such as allows the wearer to make speed in the water especially when using the 30 well known "scissors-stroke" wherein the legs are moved towards and away from each other in a substantially horizontal plane.

Considered from another angle, I have evolved and produced a practical appliance 35 for foot and hand use wherein two pairs of the appliances are generally provided and wherein the hinged swingable wings thereof are attached in reverse order, for example, one being attached so that the wings extend 40 rearwardly and the other attached so that the wings extend forwardly, thereby promoting a desirable alternate propulsion action such as insures quick propulsion in the water.

Other features and advantages will become 45 more readily apparent from the following description and drawings.

In the drawings:

Figure 1 is a perspective view showing a pair of the appliances attached to the feet of 50 the wearer.

Figure 2 is an open plan view.

Figure 3 is also an open plan view of the frame constituting an important part of the structure.

Figures 4 and 5 are sectional views taken approximately upon the plane of the lines 55 4-4 and 5-5 respectively of Figure 2.

Figure 6 is a cross sectional view through the device showing a slightly modified form 60 of the invention.

In the drawings it will be seen that the appliance is principally constructed of a pair of duplicate propelling elements which may be conveniently referred to as wings 7 and 8 respectively. These wings are joined together through the medium of a flexible rubber body which is centrally arranged and generally designated by the reference character 9 and this functions as a hinge and normally maintains the wings in the approximate angular relationship seen in Figure 4. 65 In other words, this is the closed position of the wings.

The wings and hinge may be molded from a single body of rubber. For instance, it has been found practical to construct the wings from frames of the configuration shown in Figure 3. These frames are reinforcing members and are embedded in the flexible webbed portions as well as in the hinge body. The frames comprise spaced 70 parallel bar members 10 joined to the curvate marginal members 11, the members 11 being of the plan configuration shown in Figure 3.

The reference characters 12 merely designate the cross braces. The reference numerals 13 designate connecting rings which are embedded in the hinge forming body as seen in Figure 4. The longitudinal sectional configuration of the wings is shown in Figure 5 from which it will be seen that the major portions of the wings are relatively thin, thus forming flexible webs within the area of the bar members of the two frames.

The reference characters 14 and 15 designate attaching straps having complementary adjustable buckle elements 16 and 17 respectively. The straps are of course longitudinally adjustable and slidably positioned and detachably connected in the passages 18 95 100

formed in the hinge portion of the device as seen in Figure 4.

Tapes or straps 19 may be employed to limit the outward swing of the wings as represented in dotted lines in Figure 4. Particularly do I wish to emphasize the outline configuration of these wings as well as the fact that they are formed at opposite ends with curvate flares 20 and 21 respectively.

10 In practice I provide a pair of these wing equipped appliances for the legs and these are strapped to the ankles adjacent the feet of the user as shown for example in Figure 1. As here represented, the wings of one appliance, for instance on the right leg, extend forwardly and those on the left leg rearwardly, thus reversing the order of action and to increase the leverage and power of the leg strokes. It is obvious that as the legs are moved in a swimming action, the wings of the respective appliances will flap back and forth to open and closed position to provide sufficient impact and power surface to literally drive the body through the water.

15 The fact is, these appliances allow the wearer to move through the water in skating action. As before stated, the appliances are made not only for the legs but also for the hands (not shown).

20 In the form of the invention shown in Figure 6, the wings 22 are of suitably shaped aluminum plates 23 and these are connected together by links or rings 24 embedded in the rubber hinge portion 25. Here again, the hinge portion is formed with passages 26 to accommodate the attaching straps (not shown).

25 The wings are of the same configuration and shape as already illustrated and the application and action of the appliance is practically the same as that already described. Thus it will be seen that in the principal forms of the invention I provide a flexible relatively thick rubber body constituting the hinge and possessing desirable inherent resilient properties such as normally maintain the wings closed but allows them to swing back and forth in an alternate manner while swimming.

30 The arrangement may be such as to provide rubber wings with the reinforcing frames embedded therein or aluminum wings embedded in the hinge forming body.

35 It is thought that a careful consideration of the description in connection with the drawings will enable the reader to obtain a clear understanding of the invention, the method of application and use, as well as the features and advantages of the invention. Therefore, a more lengthy description is believed to be unnecessary. Minor changes in shape, size and materials and rearrangements of details coming within the field of invention claimed may be resorted to in actual practice if desired.

I claim:

1. As a new product of manufacture, a swimmer's appliance of the class described comprising a relatively thick centrally disposed rubber body, and a pair of duplicate wings connected thereto, said body constituting a hinge and possessing normal inherent properties to maintain the wings in substantial parallelism but allowing the wings to swing outwardly to open position, and adjustable retaining straps carried by said body.

2. As a new product of manufacture, a swimmer's appliance of the class described comprising a relatively thick centrally disposed rubber body, and a pair of duplicate wings connected thereto, said body constituting a hinge and possessing normal inherent properties to maintain the wings in substantial parallelism but allowing the wings to swing outwardly to open position, adjustable retaining straps carried by said body, together with tapes connected with free edge portions of the wings and said straps to limit the swinging motion of the wings in one direction.

3. In a swimmer's appliance of the class described, a relatively thick resilient body constituting a hinge and having upper and lower transverse passages adapted to accommodate retaining straps, and a pair of duplicate wings associated with said body, said body constituting a hinge for said wings and presenting inherent resilient properties for normally maintaining the wings in closed position, there being a pair of said wings and these being joined together through the medium of links, said links being embedded in said body.

4. In a swimmer's appliance of the class described, a relatively thick resilient body constituting a hinge and having upper and lower transverse passages adapted to accommodate retaining straps, and a pair of duplicate wings associated with said body, said body constituting a hinge for said wings and presenting inherent resilient properties for normally maintaining the wings in closed position, there being a pair of such wings and these being joined together through the medium of links, said links being embedded in said body, said wings being of longitudinal curvate configuration in top plan view and being provided at their opposite ends with flared corner portions.

In testimony whereof I affix my signature.
NORMAN A. CHASTENAY.
